(57) **CLAIM**

The ornamental design for a battery charger, as shown and described.

DESCRIPTION

FIG. 1 is a top left-rear isometric view of a battery charger showing our new design.

FIG. 2 is a bottom right-front isometric view thereof.

FIG. 3 is a top right-front isometric view thereof.

FIG. 4 is a bottom left-rear isometric view thereof.

FIG. 5 is a top plan view thereof.

FIG. 6 is a bottom plan view thereof.

FIG. 7 is a rear elevational view thereof.

FIG. 8 is a front elevational view thereof.

FIG. 9 is a left side elevational view thereof; and,

FIG. 10 is a right side elevational view thereof.

The broken lines in the figures depict portions of the article which form no part of the claimed design.
